UNITED STATES PATENT OFFICE.

FRANK H. LOBB, OF MILLVILLE, NEW JERSEY, ASSIGNOR TO UNITED BOTTLE MACHINERY CO., OF NEW YORK, N. Y., A CORPORATION OF NEW YORK.

MECHANISM FOR CUTTING OFF MOLTEN GLASS.

1,388,654.

Specification of Letters Patent. Patented Aug. 23, 1921.

Application filed September 17, 1917. Serial No. 191,665.

To all whom it may concern:

Be it known that I, FRANK H. LOBB, a citizen of the United States, and a resident of Millville, in the county of Cumberland and State of New Jersey, have invented certain new and useful Improvements in Mechanism for Cutting Off Molten Glass, of which the following is a specification.

My invention relates to mechanism for cutting off molten glass, particularly for use in connection with machines for manufacturing glass articles, such as for instance glass bottles, by blowing, pressing or otherwise.

In machines of this kind the molds or other receptacles which are to receive a charge of molten glass, are generally brought into registry with an outlet opening or nozzle provided in the glass tank or furnace; this nozzle is then opened, and after the desired amount of glass has been withdrawn, the outlet is closed again, the mold removed and another mold or receptacle brought into position.

Considerable difficulty has been experienced hitherto in properly coöordinating the action of the mold-carrying machine in bringing the molds or other receptacles into glass-receiving position, and the action of the cutting device in allowing a certain amount of glass to flow into such receptacle, and then cutting off the stream of molten glass. Another difficulty has been to construct a cutting device which will be able to stand the intense heat to which it is exposed without cracking or otherwise wearing out too quickly.

One purpose of my present invention is to provide reliable and effective means for causing the cutting mechanism to be operated by the mold-carrying machine positively and at exactly the proper time.

Another object is to construct the cutting device or knife and support it in such a way that it will be exposed to the heat of the molten glass in the furnace in a practically uniform manner and will therefore not be liable to wear out prematurely.

Still another object is to so construct and support the knife that it will always be in close contact with the plate or member in conjunction with which it performs its function of cutting off the stream of molten glass.

A further object is to make the knife easily

removable for the purpose of inspection or 55 of replacing it by a new one, without having to wait until the knife and the parts connected with it have cooled off.

These and other objects and advantages 60 of my invention will be fully described hereinafter and will be claimed in the appended claims.

Reference is to be had to the accompanying drawings in which—

Figure 1 is an elevation of my improved 65 mechanism, with the lower part in section on line 1—1 of Figs. 2 and 3;

Fig. 2 is a view taken at right angles to Fig. 1, looking in the direction of the arrow 70 2 in Fig. 1;

Fig. 3 is a plan view, with parts in section and other parts omitted or broken away for the sake of clearness;

Fig. 4 is a vertical section taken substantially on line 4—4 of Fig. 3, and shown on 75 an enlarged scale;

Fig. 5 is a view similar to Fig. 4, but showing the cutting mechanism in outside view, certain parts being omitted from this view for the sake of clearness;

Fig. 6 is a section taken on line 6—6 of Figs. 3 and 4;

Fig. 7 is a partial section taken on line 70 7—7 of Fig. 6;

Fig. 8 is a detail bottom view of the cutting 85 mechanism proper;

Fig. 9 is a cross section taken on line 9—9 of Fig. 8;

Fig. 10 is a front view of the cutting mechanism proper with parts broken away for 90 the sake of clearness; and

Fig. 11 is a detail view, with parts in section on line 11—11 of Fig. 3.

Referring now to the drawings, the glass tank or furnace 20, of any approved construction, has in its side wall an outlet 21 for the molten glass, controlled by a gate 22, which outlet leads into a chamber or auxiliary furnace 23 built of fire-clay or other refractory material and supported on, or 95 connected with, the main furnace 20 in any suitable manner. Preferably the auxiliary furnace 23 rests on a bottom or sole plate 24 having a flange 25 surrounding the lower part of the auxiliary furnace 23. In the 100 forward part of the auxiliary furnace 23 is located a preferably annular vertical wall 26 enclosing a vertical discharge chamber

27 communicating with the glass outlet 21 of the main furnace and registering at its lower end with an opening in the bottom of the auxiliary furnace 23. The glass outlet proper is formed by a nozzle member 28 made of refractory material and held in place by a suitable plate 29 secured to the bottom plate 24 by screws 30 and large washers 31, the screws extending through slots 32 which, as shown in Figs. 3 and 6, are considerably wider in one direction than the screws so as to enable the plate 29 to be shifted laterally with respect to the plate 24 for the purpose of adjusting the nozzle outlet to the proper position, the opening in plate 24 into which the nozzle 28 fits being of sufficient diameter or width to allow of such adjustment. In a recess in the lower face of the plate 29 is secured a thin plate 33 in such a way that together with the adjacent portion of the plate 29 it forms a smooth surface along which the cutting or shearing member is adapted to move. This thin plate 33 is provided with an opening 34 registering with the opening in the nozzle 28 and it therefore forms or becomes part of the nozzle. In the drawings these openings have been shown as being of circular cross section, but I do not wish to limit myself to this particular shape of outlet. In Fig. 3, I have shown a top view of the plate 29 and the nozzle. The auxiliary tank 23 would not show in this view; it has, however, been indicated in dotted lines in order to show the relation between the plate 29 and the auxiliary tank 23 and also the main tank 20, the wall of the latter having been indicated in section at the extreme right in this view.

40 The cutting mechanism consists of a cutting member or knife 35 beveled on one side so as to form a sharp cutting edge 36; this cutting edge preferably conforms to a certain extent to the outline of the nozzle outlet and is preferably V-shaped, as shown best in Fig. 8. The knife or shearing member 35 has on its lower face a transverse projection or rib 37 fitting into a corresponding groove or recess 38 formed in a supporting member 39. This recess is slightly wider and longer than the rib 37 so that the knife will be supported somewhat loosely by the member 39. As will be seen from Figs. 6 and 10, the bottom of the groove is straight, while the lower surface of the rib 37 is curved or rounded toward both ends so that the knife will be in contact with its support practically along a line only, viz: in the center of the rib 37. At its forward end the knife-supporting member or knife carrier 39 is also beveled, this beveled surface having its center line in the continuation of the center line of the beveled surface of the knife. The knife carrier 39 has laterally-extending studs 40 having square portions resting in simi-

larly-shaped open top sockets 41 of a U-shaped bracket 42 connected with the screw-threaded end of a rod 43 by means of which the cutting mechanism is operated in the manner described below. The rod 43 is supported in a bearing 44 preferably integral with a lateral extension 45 of the plate 29. This bearing will guide the rod 43 and therefore also to a certain extent the knife 35. In order to insure proper contact, however, between the knife 35 and the orifice of the nozzle 28, the knife is pressed against the nozzle by the following means: On the round ends of the studs 40 are journaled rollers 46 adapted to travel on tracks 47 pivotally supported at 48 on posts 49 secured to the extension 45 of the plate 29. At their other ends, the tracks 47 are engaged by springs 50 held in place by means of pins 51 screwed into the end portions of the tracks 47 and extending loosely through brackets 52 secured to the plate extension 45. It will be clear that the action of the springs 50 on the ends of the tracks 47 will press the track portions on which the rollers 46 travel, upward against these rollers, and this upward pressure will keep the knife or blade 35 in close contact with the lower surface of the nozzle 28.

In order to further guide the knife 35 properly, that is to prevent lateral movement of the knife carrier 38 and the knife, the plate 29 is provided at its lower surface with downwardly-projecting flanges 53 extending in a direction parallel to that in which the knife reciprocates. As shown in Fig. 6, these projections 53 form together a guide for the knife carrier and prevent lateral movement of this carrier and of the knife. The knife 35 is provided with two longitudinal channels 54 and a transverse channel 55 connecting them, for the circulation of a cooling medium, which enters through one of two pipes 56, the other pipe forming an outlet for the cooling medium. Both pipes are held together by a suitable clamp 57 and are connected to flexible tubes 58.

As shown in Figs. 1, 3, 4 and 5, the free end of the rod 43 is in screw-threaded engagement with a sleeve 59 to which are pivotally secured, at opposite sides, links 60, the other ends of which are pivotally connected at 61 with a lever 62. This lever, which is extended beyond the pivot 61 to form a handle 63, is fulcrumed on the upper portion of a rock shaft 64, with which it is normally connected rigidly, so as to move in unison with this rock shaft. This connection is made by means of an arm 65 keyed to the rock shaft 64 and provided at its free end with a sleeve 66 in which is slidably mounted a pin 67 normally pressed upward into a socket 68 in the lever 62 by a spring 69. The pin 67 is provided with a milled 130

head by means of which it can be pulled out of engagement with the socket 68. As long as the pin 67 is in engagement with the socket 68, the lever 62 will participate in any movement of the rock shaft 64; as soon however as the pin 67 is pulled out of engagement with the socket 68, the lever 62 will become independent of the rock shaft 64 and can be moved by hand to any desired position by means of the handle 63. This is of advantage in case it is desired to stop the operation of the cut-off mechanism while the shaft 64 continues to be rocked. To prevent the pin 67 from being again pushed into the socket 68, the lower end of the pin 67 is provided with a cross pin 70 adapted to engage slots 71 in the sleeve 66. Normally, that is, when lever 62 and arm 65 are in operative engagement, this cross pin will extend through the slots 71, as shown in Figs. 1 and 11. When the pin 67 is pulled out of engagement with the socket 68, it is given a slight turn around its axis, so that the cross pin 70 will assume the position shown in dotted lines in Fig. 11, lying against the lower surface of the sleeve 66, and thus preventing the pin 67 from again engaging the socket 68.

The rock shaft 64 is supported at its upper end in a bearing 72 on a bracket 73 secured to the plate extension 45 referred to above, by means of screws 74. The lower end of the rock shaft 64, which is held in bearings 75 forming part of, or carried by a suitable bottom or foundation plate 76, has rigidly connected therewith, a lever 77 carrying at its free end a roller 78 adapted to be engaged by cam surfaces 79 on disks 80. Through these disks extends loosely a shaft 81, but the disks are held to rotate with said shaft in the following manner: The outer faces of these disks, that is, those opposite to the cam surfaces, are formed with radial teeth adapted to engage corresponding radial sockets in sleeves 82, 83 keyed to the shaft 81. Between the two disks, the shaft 81 is screw-threaded, and on this screw-threaded portion are carried two nuts 84 whose purpose is to press the disks firmly into engagement with the sleeves 82, 83 respectively, so as to compel these disks to rotate with the shaft 81. The lever 77 is provided with a downward projection 85 resting on an upward extension 86 of the foundation plate 76, for the purpose of properly guiding this lever in its rocking movement.

At one end, the shaft 81 is supported in a bearing 87, while its other end portion extends through a bearing 88 and carries a bevel gear 89 engaged from above by a rack or bevel-gear 90 on a rotary table or plate 91 forming part of a mold-carrying machine or device. The bearing 88 is secured to the foundation plate 76 and also

to a stationary plate or table 92 likewise forming part of the mold-carrying machine just referred to.

The mechanism forming the subject-matter of my present invention has been devised chiefly for use in connection with bottle-making machines of the well-known type where the molds or other receptacles which are to receive a charge of liquid glass, are carried on a rotary table or support, the movement of either the whole support or of the individual molds or other receptacles being temporarily arrested when these molds or receptacles have reached a position in which they can receive their charge of molten glass. In Figs. 1 and 3, 91 represents a portion of the rotary part or table of such machine, this table carrying the molds or other receptacles in any suitable manner (not shown), while 92 represents a stationary part of the same machine. One of the molds has been designated in Figs. 1 and 6 by the numeral 93. In the example shown, the mold-carrying machine rotates about a vertical axis passing through the intersection of section lines 1-1 and 6-6 in Fig. 3.

The relation between the number of teeth on the rack 90 and on the gear 89 engaged thereby is such that for each mold brought into position under the delivery nozzle, the shaft 81 will make one revolution; if for example the machine carries eight molds, the shaft 81 will be rotated eight times for one revolution of the mold-carrying machine.

The rock shaft 64 is preferably made flexible by means of universal joints 94; this is done in view of the fact that the upper part of this shaft is carried by the auxiliary furnace 23 which is liable to expand, while the lower part of this shaft is carried by the foundation plate 76 which is not likely to expand, at least not to the same extent as the chamber 23.

In the drawings, particularly in Figs. 1, 4 and 6, I have shown interposed between the mold 93 and the delivery nozzle 28, a transfer funnel 95 through which the glass issuing from the nozzle will pass before it reaches the mold 93. Preferably integral with this funnel is an inclined chute 96 which, when desired, can be moved into registry with the nozzle instead of the transfer funnel 95, so that the glass issuing from the nozzle will not drop into the mold, but will be led away down the inclined chute 96 into a water tank (not shown). The transfer funnel 95 and chute 96 and the mechanism for operating them, however, form no part of my present invention, and they will therefore be described but briefly in the present application. As shown in Figs. 4, 5 and 6, the transfer funnel 95 is supported by guides 97 screwed to down-

ward extensions 98 of the plate 29. (In Fig. 5, the funnel 95 has been omitted for the sake of clearness.) To the sides of the chute 96 are secured brackets 99 connected by a pivot pin 100 to one end of a link 101 the other end of which is pivotally connected at 102 to a crank arm 103 rigidly secured to a rod 104 supported in a bracket 105 attached to the bottom plate 24 of the auxiliary furnace 23. To the outer end of the rod 104 is secured rigidly a lever arm 106 having at one end a weight 107, and at the other end a sector-shaped portion 108, the straight or radial surfaces of which are adapted to engage the ends of screws 109 mounted adjustably in the bracket 105. In the position in which the lever 106 is shown in Fig. 6 (engaging the left-hand screw 109), the transfer funnel 95 is in registry with the nozzle outlet 28; if now the lever arm 106 is brought to the position where its sector-shaped portion engages the other screw 109, this will shift the transfer funnel 95 to the left in Fig. 6, bringing the chute 96 into registry with the nozzle outlet 28. The transfer funnel is preferably water-cooled, the water entering through pipe 110 and issuing through holes 111 into the chute 96 along which it flows down into the water tank referred to above.

The operation of my improved mechanism is, briefly described, as follows: With the parts in the position shown in Figs. 1, 3, 4, 5 and 6, the blade or knife 35 closes the outlet in the nozzle 28 so that no molten glass will issue from the discharge chamber 27. As described above, the shaft 81 is rotated through the rotating movement of the table 91 carrying the molds or other receptacles which are to receive a charge of molten glass. As soon as the raised cam portion on the left-hand disk 80 pushes the roller 78 on lever 77 over toward the right (Fig. 3), the shaft 64 will be rocked and this will cause the knife 35 to be withdrawn from the nozzle outlet and allow molten glass to flow out and drop through the transfer funnel 95 into the mold or other receptacle, which at this time will be in receiving position. The two cam surfaces on the disks 80 are so arranged that as soon as the desired amount of molten glass has been withdrawn or dropped into the mold or other receptacle, the cam surface on the right-hand disk 80 will again push the roller 78 over toward the left (Fig. 3), causing the shaft 64 to be rocked and the blade or knife 35 to cut off the stream of molten glass issuing from the nozzle outlet 28.

The length of time during which the blade 35 is withdrawn from the nozzle opening and the glass allowed to flow out, can be regulated at will by adjusting the cam surfaces on the disks 80 with respect to each other. For this purpose, the nuts 84 are

loosened and the disks 80 slid out of engagement with the sleeves 82, 83, whereupon the disks can be turned until the cam surfaces have the proper relation to each other. The nuts 84 are then tightened again and the disks will be securely held in the positions to which they have been adjusted, owing to the engagement of their toothed surfaces with the corresponding surfaces on the sleeves 82, 83.

If for any reason the glass supply should have to be stopped suddenly before the mold-carrying machine can be brought to a standstill, this can be done quickly by pulling the pin 67 out of the socket 68 and moving the blade 35 by means of the handle 63 to a position in which it will close the nozzle outlet. The mold-carrying machine may then continue to run without operating the knife-mechanism, the small cross pin 70 preventing the pin 67 from returning into engagement with the socket 68. On the other hand, it may be desirable to allow molten glass to flow out of the nozzle, irrespective of whether there is a mold in registry with the nozzle or not. In this case, the knife can be brought to a position where it uncovers the nozzle, in the same manner as just described in connection with the closing of the outlet. This procedure may be followed for instance if after the machine has been in operation a certain length of time it is desired to stop working. In this case, the gate 22 will first be closed, then the nozzle outlet opened, and all the molten glass contained in the auxiliary furnace 23 is allowed to flow out and down the inclined chute 96, which has been brought into position under the nozzle in the manner described above.

The mechanism employed by me for operating the glass-cutting device is positively-acting and is much more effective and reliable than for instance pneumatic means commonly employed for this purpose. Another important advantage of my invention resides in the special construction of the knife and the manner of supporting it. In devices of this kind, great difficulty has been experienced in finding a suitable closing means for the outlet nozzle, which will stand the intense heat to which it is exposed during the time that the outlet is closed, without cracking or otherwise wearing out prematurely. By supporting the knife or closing means in the manner shown and described, that is, by providing it with a rib or projection fitting into a corresponding groove in the knife carrier, I am enabled to make the knife of relatively small surface area, and especially of a considerably smaller length (in the direction of its movement) than has been possible hitherto with a knife connected to its operating mechanism at its rear end. A small knife, that is, a narrow

and short knife, is exposed to the heat more uniformly than a knife of larger surface area, which latter is more liable to cracking on account of the difference in temperature between the inner portions in actual contact with the molten glass and the outer portions which are more remote from the nozzle outlet and therefore heated to a considerably smaller degree. A small knife will therefore give much better wear than a large one.

Another advantage of using a small knife supported loosely and being in contact with its carrier along a line only, is that it will lie more closely against the plate on which it is adapted to slide and in conjunction with which it cuts the stream of molten glass. This plate is liable to warp considerably owing to the intense heat of the molten glass in the furnace, and a small knife which is pressed against such plate and supported in the manner shown and described, will follow to a certain extent the distorted or warped surface of the plate; in any event, it will do this to a greater extent than a wider or longer knife. A small knife such as I am enabled to use by my invention, will therefore make a cleaner cut than a knife of larger surface area.

Still another advantage of my new manner of supporting the knife is the ease with which the knife can be inspected, removed for repairs, or replaced with a new one. All that is necessary for this purpose is to remove the pins 51 in the ends of tracks 47, whereupon these tracks can be swung on their pivots 48 until either the knife itself can be lifted from its carrier, or this carrier together with the knife can be lifted out of engagement with the U-shaped bracket 42 after disconnecting the latter from rod 43. In either case, the pipes 56 will of course have to be disconnected from the flexible tubes 58. It is also obvious that before the knife is removed, the auxiliary furnace will have to be emptied in the manner described above. There is no need of waiting, however, until the auxiliary furnace has cooled off, since the only screws which have to be loosened are remote from the furnace and therefore have not been exposed to intense heat. Since the knife can then simply be removed by lifting it out of its support or carrier, or lifting this support out of the U-shaped bracket, the heated condition of these parts does not interfere with the removal of the knife.

I claim as my invention:

1. In a device of the character described, a discharge chamber having an outlet, a shearing member movable across and in contact with said outlet and provided on its lower surface with a rib transverse to the path of said shearing member, a carrier located under the shearing member and hav-

ing a transverse groove in which said rib is seated to compel said member and carrier to move in unison across the outlet and to prevent the shearing member from turning relatively to the carrier about a vertical axis, and means for moving said carrier. 70

2. In a device of the character described, a discharge member having an outlet, a shearing member movable across and in contact with said outlet and provided with a transverse rib on its lower surface, the bottom of said rib being curved, a carrier located under the shearing member and having a transverse groove with a surface engaged by said rib along a single line parallel to the path of the shearing member, and means for moving said carrier. 75

3. In a device of the character described, a discharge member having an outlet, a shearing member movable across and in contact with said outlet, a carrier with which the shearing member is connected loosely to rock relatively thereto whereby the shearing member is enabled to adapt itself to irregularities in the shape of the coöperating outlet surface, and means for moving said carrier. 90

4. In a device of the character described, a discharge member having an outlet, a shearing member movable across and in contact with said outlet, a carrier with which the shearing member is connected loosely to rock relatively thereto about an axis parallel to the path of the shearing member whereby the shearing member is enabled to adapt itself to irregularities in the shape of the coöperating outlet surface, and means for moving said carrier. 100

5. In a device of the character described, a discharge member having an outlet, a shearing member movable across and in contact with said outlet, a carrier located on the side of the shearing member opposite to that facing the outlet, said carrier and shearing member being provided, on their adjacent surfaces, with coöperating rib and groove 110 formations transverse to the path of the shearing member, to compel said member and carrier to move in unison across said outlet while preventing the shearing member from turning relatively to the carrier about an axis transverse to the path of the shearing member, and means for moving said carrier. 115

6. In a device of the character described, a discharge chamber having an outlet, a shearing member movable across said outlet, and having a V-shaped beveled cutting edge, a carrier for said shearing member provided with an inclined surface alining with that portion of the cutting edge which forms the angle or corner of the V, and means for moving said carrier. 120

7. In a device of the character described, a discharge chamber having an outlet, a

- shearing member movable across said outlet, a carrier for said shearing member, provided with lateral studs, a forked bracket engaging said studs, and means for moving 5 said bracket.
8. In a device of the character described, a discharge chamber having an outlet, a shearing member movable across said outlet, a carrier for said shearing member, provided with lateral studs, a forked bracket 10 engaging said studs, rollers mounted on the studs, a track on which said rollers are adapted to travel, and means for moving said bracket.
15. 9. In a device of the character described, a discharge chamber having an outlet, a shearing member movable across said outlet, a carrier in which said shearing member is seated loosely, a track on which said carrier 20 is movable, said track itself being movable toward and from the outlet, means for pressing the track toward the outlet, and means for moving the carrier.
25. 10. In a device of the character described, a discharge member having an outlet, a shearing member movable across and in contact with said outlet, a carrier located on the side of the shearing member opposite to that facing the outlet, said carrier and shearing member being provided, on their adjacent faces, with coöperating rib and groove 30 formations transverse to the path of the shearing member, said rib being in contact with the groove along a single line parallel 35 to the path of the shearing member, and the shearing member being adapted to rock on the carrier transversely of said path, and means for moving the carrier.
40. 11. In a device of the character described, a discharge member having an outlet, a shearing member movable across and in contact with said outlet, a movable carrier for said shearing member, the said carrier and shearing member being provided, one with 45 a rib extending transversely of the path of the shearing member and curved in said direction at its free surface, and the other with a transverse groove with the surface of which said curved surface of the rib is in 50 rocking engagement, and means for operating said carrier.
55. 12. In a device of the character described, a discharge member having an outlet, a shearing member movable across and in contact with said outlet, a movable carrier for said shearing member, the said carrier and shearing member being provided, one with a rib extending transversely of the path of the shearing member and curved in said direction 60 at its free surface, and the other with a transverse groove having a plane surface with which said curved surface of the rib is in rocking engagement, and means for moving the carrier.
65. 13. In a device of the character described, a discharge member having an outlet, a shearing member movable across and in contact with said outlet, a carrier located on the side of the shearing member opposite to that facing the outlet, said carrier being in 70 loose engagement with the shearing member so that the latter can be separated from the carrier by moving one relatively to the other in a direction transverse to the path of the carrier, and means for operating the carrier. 75
14. In a device of the character described, a discharge member having an outlet, a shearing member movable across and in contact with said outlet, a movable carrier for said shearing member, provided with a 80 transverse groove on its face adjacent to the shearing member, while the latter has a transverse rib set in said groove loosely to permit of the ready separation of the shearing member from its carrier by moving one 85 relatively to the other in a direction transverse to the path of the carrier, and means for operating the carrier.
15. In a device of the character described, a discharge member having an outlet, a 90 shearing member movable across said outlet, stationary guides for preventing lateral movement of the shearing member while allowing it to move across said outlet and also toward and from the outlet, a track 95 engaged by said shearing member and movable toward and from the outlet relatively to said stationary guides, means for pressing said track toward the outlet, and means for operating the shearing member. 100
16. In a device of the character described, a discharge chamber having an outlet, a shearing member movable across said outlet, an actuating rock shaft having an arm oscillating therewith, a lever operatively 105 connected with said shearing member and mounted to rock about the axis of said shaft, and means for connecting said arm and lever for joint movement or disconnecting them to allow the rock shaft to oscillate without 110 operating the shearing member.
17. In a device of the character described, a discharge chamber having an outlet, a shearing member movable across said outlet, an actuating rock shaft having an arm oscillating therewith, a lever operatively connected with said shearing member and mounted to rock about the axis of said shaft, and a connecting device carried by one of 115 said rocking elements and movable parallel to the axis of the rock shaft to connect the arm and lever for joint movement or disconnect them to allow the rock shaft to oscillate without operating the shearing member. 120
18. In a device of the character described, a discharge chamber having an outlet, a shearing member movable across said outlet, an actuating rock shaft having an arm oscillating therewith, a lever operatively connected 125 with said shearing member and

nected with said shearing member and mounted to rock about the axis of said shaft, a connecting pin carried by one of said rocking elements and movable parallel to the axis of the rock shaft to connect or disconnect said arm and lever, and a spring tending to hold said pin in the connecting position.

19. In a device of the character described, 10 a discharge chamber having an outlet, a shearing member movable across said outlet, an actuating rock shaft having an arm oscillating therewith, a lever operatively connected with said shearing member and 15 mounted to rock about the axis of said shaft, a connecting pin carried by one of said rock-

ing elements and movable parallel to the axis of the rock shaft to connect or disconnect the said arm and lever, said pin being also mounted to turn about its own axis, the pin and the element carrying it having mating formations which prevent the longitudinal motion of the pin to the connecting position when the pin is turned to a certain position, but allow such longitudinal motion when the pin is in its normal position, and a spring tending to move said pin lengthwise to its connecting position.

In testimony whereof I have signed this specification.

FRANK H. LOBB.
